UNITED STATES PATENT OFFICE.

DAVID G. GRIFFIN, OF CHATTANOOGA, TENNESSEE.

CHEMICAL CONTAINER.

Application filed December 23, 1924. Serial No. 757,684.

This invention relates to an insect exterminator, and aims to provide a container of novel construction to be supported on a plow in such a manner that the plants under 5 cultivation will be treated by the fumes passing from burning chemicals contained in the device.

An important object of the invention is to provide a device of this character 10 which may be readily and easily positioned, and one wherein the cleaning and refilling of the device may be accomplished with facility.

With the foregoing and other objects in 15 view which will appear as the description proceeds, the invention resides in the combination and arrangement of parts and in the details of construction hereinafter described and claimed, it being understood that 20 changes in the precise embodiment of the invention herein disclosed, may be made within the scope of what is claimed, without departing from the spirit of the invention.

25 Referring to the drawing:

Figure 1 is a plan view of a container or receptacle constructed in accordance with the invention.

Figure 2 is a longitudinal sectional view 30 therethrough.

Figure 3 is an elevational view of one end of the container.

Figure 4 is a sectional view taken on line 4-4 of Figure 2.

35 Referring to the drawing in detail, the body portion which is cylindrical in formation is indicated generally by the reference character 5 and is constructed preferably of sheet metal, although it is to be understood 40 that suitable material such as asbestos or the like may be employed in the manufacture of the body portion.

Extending throughout the length of the body portion and arranged in spaced relation 45 with each other are the openings 6, which openings establish communication between the interior of the body portion and atmosphere to allow the smoke and fumes from the burning material to pass outwardly 50 from the body portion.

The body portion is formed with an elongated opening formed in the upper surface thereof, which opening allows a person to place the chemical to be burned within the body portion, and at the same time affords 55 means to permit the interior of the body portion to be cleaned with facility.

Arranged on opposite sides of the elongated opening are flanges 7 that provide guideways for the sliding closures 8 formed 60 with upwardly extended end portions 9 that afford means whereby the closures may be readily slid from their active positions to uncover the openings, or vice versa.

The closures 8 are also formed with openings indicated at 10 that allow the smoke and fumes to pass directly upwardly from the container. The reference character 11 indicates closures that fit within the ends 70 of the body portion, and as shown, these closures are formed with handles 12 to facilitate the positioning and removal of the closures. Formed in the closures 11 are openings 13 which allow the fumes to pass from the ends of the body portion, and at 75 the same time allow air to enter the body portion 5 to insure perfect combustion within the body portion.

Supported centrally of the body portion 80 is a band 14 which has right angled end portions 15 formed with openings to accommodate the bolt 16, by means of which the band may be moved into close engagement with the body portion to clamp the body portion against movement. The band is 85 provided with an offset portion 17 which may be positioned over a suitable beam of a plow or the like, so that when the bolt 16 is properly positioned, the band will support the body portion on a plow. 90

In the use of the device, a suitable chemical is placed within the body portion and lighted, it being understood that the body portion is positioned on a plow so that the fumes passing therefrom will come in direct 95 contact with the plants under cultivation.

Due to the nature of the chemicals burned, the fumes arising from the device will be poisonous to insect life to destroy the same. 100

I claim:—

In a device of the character described, a tubular body portion, removable covers for normally closing the ends of the body portion, said body portion having a longitudinal cut out portion, sliding closures for normally closing the longitudinal cut out portion, said body portion and sliding clo-

sures having openings to allow fumes to pass therethrough, and a supporting band adapted to be clamped around a supporting beam. 10

In testimony that I claim the foregoing as my own, I have hereto affixed my signature.

DAVID G. GRIFFIN.
